ABSTRACT: A food-treatment apparatus having an air circulator for displacing heated air in a food-treatment chamber has washing means to permit easy cleansing thereof. The washing means is a pipe which introduces a cleansing liquid into the path of air circulation so that this liquid is distributed through the apparatus.

FOOD-TREATMENT APPARATUS WITH WASHING MEANS

My invention relates to a food-treatment apparatus with washing means.

Food-treatment apparatuses are known for the cooking and warming of meat, baked goods, and other comestibles. Such apparatuses often are equipped with an air-circulating blower which recirculates the air in the apparatus through a heater to heat the food.

Such apparatuses present one enormous difficulty: they are extremely difficult to clean. Many of their interior surfaces, which are covered with the residue of many cooking operations, are nearly inaccessible and necessitate near total disassembly of the apparatus to clean it properly. This obviously is a lengthy, difficult, and, above all, expensive operation.

Therefore it is an object of my invention to provide an apparatus in which this cleansing operation is facilitated.

I do this by providing my apparatus with washing means in the form of a circular spray pipe disposed in front of the axial input of an axial-input radial-output blower serving as the air-circulating blower for my invention. Cleansing liquid can be introduced through this spray pipe into the path of the circulating air and can thereby be spread all over the interior surfaces of the apparatus. This spray pipe is advantageously circular so that the air sucked through it by the blower entrains the cleansing liquid extremely well.

My invention will be more specifically described in the following with reference to the accompanying drawing in which:

FIG. 1 is a vertical section through the apparatus according to my invention;

FIG. 2 is a section taken along line II-II of FIG. 1; and

FIG. 3 is an elevation of the spray nozzle.

A housing 9 defines a food-treatment chamber 5 which encloses a rack 14 fitted with ledges 15 on which a shelf 17 carrying a piece of food 18 can slide. The rack 14 is spaced from the housing 9 by spacers 19 defining areas 4 and 5 and by perforated plates 20 and is formed with slots 16 for passage of air therethrough.

A blower 1 mounted on a partition 12 and powered by a motor 11 enclosed by a plate 10 has axial input 1a and radial outputs 1b. This blower 1 displaces air heated by a heating element 2 through the chamber 5 and spaces 3 and 4 and sucks it in again through a hood 6 for recirculation.

Directly in front of this axial input 1a is a circular spray pipe 7, having a circular pipe 7b provided with an inlet 7a and spray

nozzles 7c, which can dispense cleansing liquid—preferably an alkaline solution or organic solvent to dissolve fats—into the input 1a of the blower 1.

A door 21 is hinged at 22 to permit access to the chamber 5.

5 In order to claim the apparatus, cleansing liquid is simply versed into a cup 8 while the blower 1 is running. This liquid is sucked into the axial input 1a and blown out through the output 1b and thereby spread all over the interior surfaces of the apparatus. Every surface which is customarily reached by the 10 circulating air and therefore covered with cooking residue is reached by this liquid and thus washed. After allowing a brief period for the liquid to soak in, the most exposed surfaces can simply be rinsed or wiped off, and the apparatus is cleaned inside.

15 The improvement described and illustrated is believed to admit of many modifications within the ability of persons skilled in the art, all such modifications being considered within the spirit and scope of the invention except as limited by the appended claims.

20 I claim:

1. A food-treatment apparatus, comprising: housing means defining a food-treatment chamber; air circulating means including a blower having an

25 housing means defining a food-treatment chamber; air-circulating means including a blower having an axial input and a radial output in said housing means for displacing heated air along a circulation path passing through said chamber; and washing means arranged in front of said axial input and located proximal to said air-circulating means, said washing means including a substantially circular spray pipe lying in a plane substantially transverse to said path for introducing a cleansing liquid for said chamber into the circulated air along a portion of said path.

30 35 2. The apparatus defined in claim 1 further comprising heating means disposed adjacent said radial output for heating the air emerging therefrom.

3. A food-treatment apparatus, comprising housing means defining a food-treatment chamber; an air-circulating blower

40 45 in said housing means for displacing heated air along a circulation path passing through said chamber, said blower having an input for drawing air along said path and an output for expelling the air into said chamber; and a spray pipe disposed in front of said input for discharging a spray of cleansing liquid into the circulating air drawn into said blower and passing along said path.
